C. A. BROWN.
COIL BOX PROTECTOR.
FILED APR. 15, 1920.

1,443,001.

UNITED STATES PATENT OFFICE.

CHARLES ANDREW BROWN, OF LOUISVILLE, KENTUCKY.

COIL-BOX PROTECTOR.

Application filed April 15, 1920. Serial No. 374,166.

To all whom it may concern:

Be it known that I, CHARLES ANDREW BROWN, a citizen of the United States, residing at Louisville, in the county of Jefferson 5 and State of Kentucky, have invented certain new and useful Improvements in Coil-Box Protectors; and I do declare the following to be a full, clear, and exact description of the invention, such as will enable 10 others skilled in the art to which it appertains to make and use the same.

My invention relates to devices for protecting coil boxes of automobiles, particularly the Ford coil box, against water, and 15 my principal object is to improve upon the protector disclosed in my pending U. S. application, Serial No. 303186, filed June 10, 1919, by spacing the upper edge thereof rearwardly from the dash to insure that any 20 water running down said dash, will not enter between the protector and the coil box.

The preferred form of the protector is constructed of rubber or other flexible material and another object is to provide spaced 25 projections on such protector for positively holding its upper edge in properly spaced relation with the dash.

A still further object is to provide a device which may be easily and inexpensively 30 manufactured and marketed, yet one which will be highly efficient and desirable in every way.

With the foregoing in view, the invention resides in the novel features of construction hereinafter described and claimed, 35 the descriptive matter being supplemented by the accompanying drawings.

Fig. 1 illustrates a vertical section of the dash of an automobile, together with a side 40 elevation of the coil box, and an edge view of the improved protector, the insulator of one of the binding posts and the guard for such insulator being partly broken away and in section.

Fig. 2 is a front elevation of the parts shown in Fig. 1.

Fig. 3 is a horizontal section as indicated by line 3—3 of Fig. 2.

Fig. 4 is a perspective view of one of the 50 protectors, and Fig. 5 is an edge view thereof.

In the drawings above briefly described, I have shown the dash D, cowl C, and hood H of a Ford automobile, said dash being 55 provided with the usual openings O through which the insulated binding posts P extend

from the coil box B. The box B is provided with vertical attaching flanges F which are bolted to the dash D, said flanges being provided with inwardly extending ears E to 60 which the front side S of the coil box is secured by screws S'. All of these parts are of well known formation and are merely illustrated and briefly described for the purpose of disclosing the manner in which 65 the present invention is used.

The improved protector comprises a preferably rectangular sheet 1 of any suitable material, although rubber is preferred. This sheet is clamped between the coil box 70 B and the dash D and its vertical edges are preferably thinned as indicated at 2 for disposition between the flanges F and the aforesaid dash. By thinning the edges of the sheet 1 in this manner, the body portion 75 thereof may more readily engage the coil box as shown in Fig. 3, suitable sockets 4 being by preference formed in said sheet to receive the screws S'. The front side of the sheet 1 is provided with a plurality of 80 binding post guards 5 which are preferably of tubular form as shown, the inner ends of said guards being joined integrally to said sheet, while the other ends of said guards are provided with ribs 6 which prevent any 85 water from running off the ends of the guards onto the several wires which are connected to the binding posts. The guards 5 and their ribs 6 are shown in the pending application above referred to and they are 90 not, therefore, broadly claimed in the present application.

To insure that any water running down the rear side of the dash board D shall not enter between the sheet 1 and the coil box 95 B, I direct the front side of said sheet rearwardly at its upper end as shown at 7, this rearward offset being preferably accomplished by beveling the sheet 1 as shown, although said sheet might be otherwise 100 thinned at its upper edge should this be desired. The bevel or the like 7 is shown provided with forwardly extending projections 8 which are preferably formed integrally with the sheet 1, said projections being 105 adapted to contact with the dash D and thus positively hold the upper ends of the protector spaced rearwardly the proper distance therefrom. These projections also serve to hold the rear side of the protector in fluid 110 tight contact with the front side of the coil box cover.

By constructing the device in, or substantially in the manner shown and described, it will positively prevent any water entering the coil box and interfering with proper operation of the ignition circuit of the machine, particular emphasis being laid upon the fact that any water running down the rear side of the dash board D cannot by any chance enter between the protector and the coil box, due to the rearwardly directed upper edge of said protector, but must seep downwardly between the protector and the dash, eventually escaping through the openings O or at the lower edge of the protector. In taking this course, the water produces no injurious effect whatever.

The device is extremely simple and inexpensive, and may be easily and advantageously manufactured and marketed, yet will be highly efficient and in every way desirable, and since excellent results have been obtained from the exact construction shown, this construction is by preference followed. I wish it understood however that within the scope of the invention as claimed, numerous minor changes may well be made.

I claim:

1. A coil box protector comprising a sheet of flexible water proof material adapted to be held between the coil box and an apertured dash and having binding post

guards to extend through the apertures of the dash, the dash engaging side of said sheet having spaced projections at or near its upper edge to space said edge from the dash.

2. A coil box protector comprising a rectangular sheet of flexible water proof material adapted to be clamped between the coil box and an apertured dash, the front side of said sheet having binding post guards to extend through the apertures of said dash, the upper edge of said sheet being beveled from the front side and having forwardly extending projections to space it from the dash.

3. A coil box protector comprising a rectangular sheet of flexible water proof material adapted to be clamped between the coil box and an apertured dash, the front side of said sheet having binding post guards to extend through the apertures of the dash, the upper edge of said sheet being thinned and having forwardly extending projections to space it from the dash, the vertical edges of said sheet being thinned for clamping between the dash and the attaching flanges of the coil box.

In testimony whereof I have hereunto set my hand.

CHARLES ANDREW BROWN.
